TYING MACHINE TABLE

Walter D. Ayres, Jr., Chicago, Ill., assignor to B. H. Bunn Company, Chicago, Ill., a corporation of Illinois
Filed July 8, 1964, Ser. No. 381,155
8 Claims. (Cl. 100—7)

This invention relates to tying machines and particularly to a mechanism for ejecting tied bundles from a tying machine.

In a co-pending application of Benjamin H. Bunn, Serial No. 278,031, filed May 6, 1963, for Apparatus for Tying Moving Bundles, now Patent No. 3,160,088, there is disclosed a conveyorized system for tying bundles of mail with both a long tie and cross-tie. In that system, a bundle of mail is placed between clamps on a moving conveyor which carries the bundle past a bundle compacting and tying machine for tying a longitudinal tie around the bundle. The bundle is then removed from the conveyor and placed upon a transfer conveyor from which it is pushed upon a second tying machine for tying the cross-tie. The second tying machine shown in the aforesaid Bunn pending application is of the type known as a "ring tying machine." In this type the usual twine arm is replaced by a ring which is driven by a chain and which carries the equivalent of a twine arm. The purpose of the ring is to permit the tied bundle to be pushed through the machine to the next station of the system without changing the direction of the bundle. It is thus possible to set up a straight line operation through the second tying machine by merely feeding the bundles in a single direction to the tying station on the machine and then through the ring off the machine and into a waiting receptacle or the like.

In automated equipment it is desirable to have the same general types of tying machines for both the long and cross ties, both for ease of repair and for uniformity of result. The ring tying machine of the aforesaid system is different from the machine used to make the first tie and hence it does not satisfy the basic requirements of automated equipment in the aforementioned system.

It is an object of this invention to provide a bundle ejecting mechanism for a tying machine which is adapted for use with substantially the same machine as is normally used for tying bundles, that is, for a standard tying machine.

As a more specific object, this invention seeks to provide a platform for supporting a bundle to be tied on a tying machine, said platform having a deflector for turning the tied bundle to one side when it is moved forwardly into the machine beyond the tying stage, and with ejecting means which propels a tied bundle forwardly against said deflector.

As a further specific object, this invention has within its purview the provision of a combined table and deflector for a tying machine wherein the table has a downwardly directed section and a deflector which deflects a forwardly moving bundle toward the downwardly directed section to cause said bundle to be turned and moved downwardly by gravity off said table.

Another object of this invention is to provide a solenoid-operated ejector mechanism for propelling a tied bundle off a tying machine, said mechanism being efficient and rapid in operation, and concealed when not in operation.

These and other objects of this invention will become apparent from the following detailed description when

2

taken together with the accompanying drawings in which:

FIG. 1 is a side elevational view of a tying machine and ejector made according to this invention and shown in position at the output end of a transfer-conveyor;

5 FIG. 2 is a plan view of the transfer-conveyor, tying machine and ejector of FIG. 1;

FIG. 3 is an elevation in section through the machine showing the details of the ejector, said section being taken along lines 3—3 of FIG. 2 and looking in the direction of the arrows at the ends thereof;

10 FIG. 4 is a greatly enlarged section through the tying machine table of FIG. 2 taken along lines 4—4 of FIG. 2 and looking in the direction of the arrows at the ends thereof; and

15 FIGS. 5, 6, 7 and 8 are fragmentary enlarged views of the ejector in successive stages of operation thereof.

20 In its preferred form, this invention comprises a tying machine which is provided with a standard twine arm rotating about an axis which is horizontal and aligned generally with the direction in which bundles to be tied are fed to the machine. A fixed table for the bundle is provided on the machine, and secured to the underside of the table is a transverse shaft on which is mounted an ejector finger. The shaft is mounted to oscillate about its

25 axis, the driving force being a solenoid which acts upon a crank arm secured to the shaft, and the restoring force is a spring. The ejector finger is disposed in an opening in the table and swings through this opening against the underside of the bundle to raise one end thereof and propel the bundle toward the twine arm. Adjacent the fixed table is a second table provided with means for deflecting the bundle horizontally and also with means for allowing the bundle to fall sidewise off the table.

25 Referring now to the drawings for a detailed description of the invention, and particularly to FIG. 2, the tying machine is shown at 10, disposed adjacent the exit end of a transfer conveyor 11, which, in turn, is disposed at the exit end of a horizontal conveyor 12 from which bundles of mail tied together with a long tie are received. 40 Conveyor 12 is provided with drive sprockets 13 and 14 which drive a chain on which are mounted clamps for holding bundles of mail 15 (shown dotted). The details of construction of the conveyor 12 are explained more fully in the aforesaid pending application of Benjamin H. Bunn and do not form a part of this invention.

45 The bundles 15 are moved toward transfer conveyor 11 on which is provided a platform 16 disposed transversely of the direction of movement of conveyor 12 and constructed to receive the bundles of tied mail, or the like, from conveyor 12. One such bundle resting on platform 16 is shown in dotted outline at 17.

50 Transfer conveyor 11 is of the push type and has one or more fingers 19 which extend downwardly into a groove 20 in the platform 16, and which are secured to a chain 21 passing over a series of sprockets 22, 23, 24 and 25 (FIG. 1), one of which sprockets 24 is driven by a mechanism shown generally at 26, to cause said fingers 19 to move along platform 16 from left to right, as viewed in FIG. 2. The mechanism 26 is described in greater detail in the aforesaid application of Benjamin H. Bunn.

55 It is contemplated that a bundle of mail 17 deposited on table 16 by conveyor 12, and having a single longitudinal tie 18, will be propelled to the right, as viewed in FIG. 2, by a finger 19 to approximately the position shown by bundle 27 shown in dotted outline on tying machine 10.

60 Tying machine 10 is of the type disclosed in FIGS. 1 and 2 of Benjamin H. Bunn, U.S. Patent No. 1,606,290,

granted November 9, 1926. The details of construction thereof are not a part of this invention. Said tying machine 10, is provided with a frame 28 on which is mounted a bearing 29 containing a hollow sleeve 30, which is adapted to be rotated by a gear 31 through appropriate driving mechanism in the machine (not shown). The axis of rotation of the sleeve 30 is substantially parallel to the direction of movement of a bundle from platform 16 to tying machine 10. As may be noted from FIG. 1, the frame 28, and particularly the bearing 29, gear 31 and sleeve 30, are directly in line with the path of a bundle 17, as it is moved from platform 16 to tying machine 10.

Secured to sleeve 30 is a twine arm 32 (FIG. 1), which is thus rotatable about the axis of sleeve 30. Said twine arm is hollow and has a twine 33 threaded therethrough and through the sleeve 30, from a suitable ball or spool (not shown).

Adjacent platform 16 is a stationary table 34, which forms part of tying machine 10 and is mounted on the frame 28 thereof. Disposed over table 34 is a yoke 35 (FIG. 3) which is secured to a post 36 and is reciprocable in a vertical direction with respect to table 34. The mechanism for reciprocating said post and yoke is not a part of this invention and hence will not be described in detail. The function of yoke 35 is to compress and hold bundle 27 against table 34 while said bundle is being cross-tied.

The standard tying machine also has a second table which is flat and aligned with table 34, the second table being mounted within, and freely rotatable with respect to, the sleeve to which twine arm 32 is secured. The second table provides support for the portion of the bundle which extends beyond the cross-tie. In such standard machines the bundle is usually inserted and removed by hand, and hence the presence of the twine arm and frame, etc., presents no problems, since the bundle may be withdrawn from the side from which it is inserted into the machine. In the present instance, however, the bundle 27 is to be ejected by a forward movement of an ejecting mechanism operating against the bottom rear portions of the bundle and tending to propel it in the same direction as did finger 19, i.e., directly toward the twine arm and its bearing and sleeve. It is necessary, therefore, to deflect the bundle so that it will move sideways and downwardly off the machine, despite the forward direction of the force upon the bundle.

The novel table employed with tying machine 10 to effect a sidewise and downward movement of a bundle, is shown at 37 in FIGS. 1, 2 and 4. Said table is comprised of a horizontal portion 38, a first downwardly sloping portion 39 and a second, more steeply inclined downwardly sloping portion 40. Said portions are suitably secured together by spot-welding or other appropriate means to form a unitary whole, and the whole is then secured to a ring 64 fixed to a shaft 65 disposed within twine arm sleeve 30. Extending transversely of the portions 38, 39 and 40 are guides 41 and 42. These guides are located at the ends of the portions 38, 39 and 40, and define a chute with said second downwardly sloping part 40. Guide 41 has a horizontal portion 43 which is co-planar with part 38 and serves to support a bundle while it is being tied. Guide 42 slopes upwardly and outwardly to avoid the creation of a rigid upright wall which would block progress of a bundle as the latter is turned and made to move downwardly into the chute 40. Guide 41 may have a vertically disposed inner wall 44, which is never contacted by the forward edge of a bundle and hence need not be sloped as is guide 42.

Horizontal portion 38 supports only one forward corner of a bundle, so that the remaining portion of the forward part of the bundle is unsupported and rests over the sloping portions 39 and 40. To cause a bundle 27 to turn and fall down sloping portions 39 and 40, a curved guide plate or deflector 45 is provided. Said guide plate is appropriately mounted upon the horizontal portion

38 and is sloped upwardly and backwardly with respect to said horizontal portion 38. It is formed with a first section 46 which, as seen in FIG. 2, is angularly disposed with respect to the forward direction of movement of a bundle, and a second section 47, which is turned to a greater extent across the forward path of movement of a bundle. The first and second sections 46 and 47 are connected by a smoothly rounded intermediate section 48, which functions to guide a corner of a bundle 27 from the first section 46 to the second section 47, said second section 47 extends over the first downwardly sloping portion 39 and also over a portion of the second downwardly sloping portion 40, as well as over guide 42. Said section 47 extends downwardly into contact with the portions 39 and 40 and with guide 42, to avoid the creation of any spaces into which one of the envelopes or other parts of a bundle may be caught.

It may thus be seen that a bundle 27, which is urged forwardly or parallel with the axis of twine arm 32 will strike the first section 46 of the curved guide plate 45 and will then be deflected by said guide plate around the intermediate section 48, upon the second section 47 and increasingly over the downwardly sloping parts 39 and 40. As the bundle progresses around guide 45, its center of gravity eventually leaves the horizontal part 43 of the guide 41 and passes over the sloping part 39, whereupon the bundle begins to tip downwardly toward chute 40. Continued movement around guide 45 brings the center of gravity of the bundle over the chute 40, whereupon the bundle is tipped further and turned by the guide 42 to slide down the chute 40. The angle of said chute with respect to the horizontal is selected to promote such downward movement of a bundle by gravity along the chute. In the present illustrative example the downward angle is 45° with respect to the horizontal, but may be varied as desired consistent with the ejecting force to be hereinafter described and with the speed with which the bundle is to be dropped down chute 40.

The ejecting mechanism is comprised essentially of a solenoid-operated lever, the latter being located at a point on the apparatus wherein it may impart an upward and forward movement to a bundle which has been cross-tied. Thus, referring to FIGS. 2, 3, 5, 6, 7 and 8, the ejecting force is supplied by a solenoid 49 of any well known construction, fixedly secured to a portion 50 of the frame of the machine and provided with a laterally extending pin 51 connected to the armature of the solenoid and adapted to move in a vertical direction. It is contemplated that pin 51 will move upwardly when the solenoid is energized and will drop back downwardly under the influence of a restoring spring, as is standard practice. Disposed over the path of movement of the pin 51 is a lever 52 secured to an oscillatable rod 53 which extends laterally from lever 52 under table 34 and terminates in a radially bent end forming a finger 54 which extends rearwardly under said table 34 and preferably in a position substantially parallel with said table 34. A slot 55 is formed in table 34, of a size large enough to permit finger 54 to pass therethrough.

Rod 53 is supported from the frame of the machine 10 by a main central bearing 56, and by two spaced bearings 57 and 58. Rod 53 is urged in one direction of rotation by a spring 59, secured at one end to a bar 60 extending laterally from the frame of the machine 10 and at its other end secured to a lever 61 extending radially outwardly from and secured to rod 53. Rod 53 is urged in the opposite direction by the aforesaid solenoid 49, acting through its armature-driven pin 51 upon lever 52. An adjustable stop 62, contacted by a lever 63 secured to and rotatable with rod 53, limits the movement of rod 53 under the action of spring 59.

For purposes of economy, it is desirable to use as small a solenoid as possible. The solenoid, however, is intended to rock rod 53 in a direction to raise finger 54 through slot 55 in table 34 and against the underside of

a bundle 27 to urge said bundle forwardly. The movement of finger 54 is to be rapid to propel the bundle rapidly forward against the deflector 45 and over the chute 40. It is characteristic of solenoids that they can move greater loads after the armatures thereof are in motion than they can when the armatures are loaded before they are energized. Accordingly, lever 52 is designed to come to rest against stop 62 when said lever 52 is spaced above pin 51, and finger 54 is designed to be spaced below the bundle 27 when lever 52 is at rest. This provides in effect a double lost motion to allow the armature of solenoid 49 to gain momentum by which to perform its bundle-ejecting function. The principal stages of operation of the ejecting mechanism are shown in FIGS. 5, 6, 7 and 8. In FIG. 5, which represents the starting position, lever 52 and finger 54 are shown spaced respectively from pin 51 and bundle 27. FIG. 6 shows the pin 51 in the next stage wherein it is moving upward across the space between it and lever 52 to acquire the momentum necessary to move the lever and its associated mechanisms upwardly. FIG. 7 shows the lever 52 in its third stage of movement, finger 54 having, in the meantime, raised bundle 27 and then caused said bundle to move forwardly while sliding down finger 54 to acquire a forward movement. FIG. 8 shows pin 51 in its final and uppermost position, with lever 52 at the end of its oscillatory movement in a counterclockwise direction, as viewed in FIG. 8, and with finger 54 having, in effect, struck the rear bottom corner of bundle 27 to give the bundle a final forward propelling blow.

The operation of the device is as follows:

A bundle such as 17, having just been removed from conveyor 12 and placed upon transfer-conveyor 11, is moved by the fingers 19 of the said transfer-conveyor to the right, as viewed in FIG. 2, to the position occupied by bundle 27. In this position, bundle 27 rests upon table 34 over slot 55 and also upon horizontal portion 38 of table 37 of the cross-tying machine 10. The yoke 35 of the hold-down mechanism is operated to compress said bundle 27 against table 34 and the tying machine 10 is then operated to cause its twine arm 32 and knotting mechanism (not shown) to tie a reach of twine 33 around said bundle and knot it in the well known manner. After the bundle is tied, solenoid 49 is energized, preferably as a function of the operation of tying machine 10, to cause its pin 51 to move upwardly to strike lever 52, which then is oscillated along with its rod 53 in the bearings 56, 57 and 58 to rotate finger 54 upwardly through slot 55 in table 34. Said finger 54 moves rapidly across the space between it and bundle 27 to strike the bottom of said bundle, as shown in FIG. 7, and then to move upwardly to cause said bundle to slide downwardly along said finger 54, and forwardly as said finger 54 continues its oscillation in a clockwise direction, as viewed in FIG. 8. Bundle 27 is thus given a forward stroke which moves it along the horizontal portion 38 of table 37 and against the curved guide plate 45. The latter turns the forward end of the bundle over the sloping portions 39 and 40 of the table 37, until the center of gravity of the bundle is over said sloping portions, whereupon the bundle falls upon the section 40 which functions as a chute to slide said bundle off machine 10.

Instead of two sloping portions 39 and 40, one smoothly rounded surface may be used which would include horizontal portion 38 and sloping portion 40. Similarly other modifications can be made in the table 37, the guide plate 45 and in the ejector mechanism without departing from the spirit of this invention.

It is understood that the foregoing description is merely illustrative of a preferred embodiment of the invention and that the scope of the invention therefore is not to be limited thereto, but is to be determined by the appended claims.

I claim:

1. In combination, a fixed tying machine table for par-

tially supporting an article to be tied, a second tying machine table adjacent the fixed table for partially supporting said article, a fixed tying machine frame member, a horizontal shaft rotatably mounted in said fixed machine frame member, and means supporting the second tying machine table from the horizontal shaft for swinging movement therearound, means for propelling an article from the fixed table to the second table, and deflector means on the second table in the path of movement of the propelled article and adapted to change the direction of the article while it is propelled.

2. The combination described in claim 1, said second table having a downwardly and laterally directed chute, and said deflector means being adapted to direct an article laterally over said chute and off said second table.

3. The combination described in claim 1, said article initially moving toward said machine frame member, a twine arm, the axis of said horizontal shaft being disposed parallel to the direction of propulsion of said propelling means, and a sleeve on, and rotatable about, said horizontal shaft, said chute being directed substantially at right angles to the direction of propulsion of said propelling means to direct said article away from said frame member.

4. The combination described in claim 1, said fixed table having a slot therein and said means for propelling the article comprising an oscillatable finger adapted to be projected through said slot against article, and means for oscillating said finger.

5. The combination described in claim 1, said fixed table having a slot therein and said means for propelling the article comprising an oscillatable rod disposed under said fixed table, a finger secured to said rod oscillatable therewith and projectable through said slot to contact said article, solenoid operated means for turning said rod in a direction to project said finger through said slot, and resilient means for withdrawing said finger through said slot.

6. The combination described in claim 5, said solenoid operated means comprising a solenoid, a pin movable by the solenoid, a lever on said rod adapted to be contacted by the pin to turn said rod, and stop means for said rod adapted to hold the lever spaced from said pin when the solenoid is deenergized to allow the solenoid to acquire momentum before operating said rod.

7. The combination described in claim 1, said swingable table having a horizontal portion adjacent to and level with said fixed table adapted to support a portion of said article, laterally and downwardly sloping portions adjacent said horizontal portion, guides at the sides of the downwardly sloping portions to define a chute for the article, and said deflector means comprising an upwardly and backwardly sloping curved guide extending across said horizontal portion and across part of said sloping portion to turn articles laterally into said chute.

8. In combination, a table for supporting an article to be tied, said table having a slot disposed under said article, a pivoted finger below said table and aligned with said slot to pass therethrough, a rod supporting said finger for oscillating movement about the axis of said rod, fixed bearings for said rod, a lever fixed to said rod and oscillatable therewith, a solenoid-operated pin reciprocable into engagement with said lever to turn said rod, resilient means acting upon the rod in opposition to the solenoid, stop means for holding said rod and said lever in a predetermined position relative to said pin against the action of said resilient means, such that said lever and pin are separated when the solenoid-operated pin is at rest, a second table for supporting a portion of the article to be tied, said second table having a horizontal portion aligned with the first table, said second table having further a chute directed downwardly and laterally of the direction of movement of said finger, and a deflector mounted upon said second table, said finger being adapted to propel an article toward the second table, and said deflector being

curved to direct the article laterally over said downwardly directed chute.
